(57) **CLAIM**

The ornamental design for a convertible drink holder as shown and described.

DESCRIPTION

FIG. 1 is a top, rear, left side perspective view of a convertible drink holder, according to the invention;

FIG. 2 is a top, rear, right side perspective view of the convertible drink holder of FIG. 1;

FIG. 3 is a left side view of the convertible drink holder of FIG. 1;

FIG. 4 is a right side view of the convertible drink holder of FIG. 1;

FIG. 5 is a front view of the convertible drink holder of FIG. 1;

FIG. 6 is a rear view of the convertible drink holder of FIG. 1;

FIG. 7 is a top view of the convertible drink holder of FIG. 1; and,

FIG. 8 is a bottom view of the convertible drink holder of FIG. 1.

The broken lines illustrate portions of the convertible drink holder that form no part of the claimed design.

1 Claim, 8 Drawing Sheets
